UNITED STATES PATENT OFFICE.

HENRY DRESES, OF CINCINNATI, OHIO.

DRILLING-MACHINE.

1,230,386.

Specification of Letters Patent. Patented June 19, 1917.

Application filed November 8, 1915. Serial No. 60,296.

To all whom it may concern:

Be it known that I, HENRY DRESES, a citizen of the United States, residing at Cincinnati, in the county of Hamilton and State 5 of Ohio, have invented certain new and useful Improvements in Drilling-Machines, of which the following is a specification.

My invention relates to that class of metal drilling machines employing an arm for supporting the drill-head, power means for raising and lowering the arm, and means for clamping the arm in adjusted positions.

In drilling machines of this character, it is a practice to clamp the drill-arm in adjusted 10 positions, the drill-arm being arranged to be unclamped when it is desired to raise or lower the drill-arm on its column, movement of the drill-arm being imparted by suitable power-propelled means for effecting the 15 raising or lowering of the drill-arm when such raising or lowering is desired. If, however, the operator is careless and does not unclamp the drill-arm prior to the movement of the drill-arm by such power-driven 20 means, excessive wear and breakage of parts 25 results from the power-application to the drill-arm while clamped to the column.

It is the object of my invention to provide means whereby to so connect the clamping 30 means for the drill-arm and the power means for raising and lowering the drill-arm as to render the power means inactive during clamped relation of the drill-arm; further to provide means whereby the power 35 means are locked in inactive relation by the clamping movement of the drill-arm clamp; and further to provide means, moving up and down with the drill-arm, having continuous connection with the power means, 40 and movement arresting means for the latter on the drill-arm clamping means.

The invention will be further readily understood from the following description and claims, and from the drawings, in which latter:

Figure 1 is a side elevation of so much of a drilling machine as is necessary to illustrate my invention.

Fig. 2 is a central vertical section of the 50 same taken on the line 2—2 of Fig. 6.

Fig. 3 is an axial section of the gearing laid out in plane.

Fig. 4 is a sectional detail showing the latch for the rockable shaft taken on the line 55 4—4 of Fig. 1.

Fig. 5 is a section of the same taken on the line 5—5 of Fig. 4.

Fig. 6 is a plan view of a drilling machine, partly broken away, and having my improved device embodied therein.

Fig. 7 is an enlarged side elevation of my improved device.

Fig. 8 is a horizontal cross-section of the same, taken on the line 8—8 of Fig. 1.

Fig. 9 is an edge elevation showing a detail of the clamp for the drill-arm.

Fig. 10 is a detail of the same in cross-section taken on the line 10—10 of Fig. 7; and,

Fig. 11 is a detail of the same in vertical 70 section taken on the line 11—11 of Fig. 7.

15 represents a usual column of a drilling machine. 16 is a drill-arm arranged to support a suitable drill-head 17, on which there is a drill-spindle 18 for containing a usual 75 drill 19. Suitable means are provided for adjusting the drill-head laterally on guide-ways 20 on the drill-arm, which may be accomplished by hand or by power, as may be desired.

The drill-arm is arranged to be adjusted up and down on the column, and is instanced as having a clamp-bearing 21 about the column for the purpose of clamping the drill-arm in adjusted positions.

The column may, if desired, be rotatable about its longitudinal axis on an annular guide 22 on the base 23 of the machine about a post 24, for the purpose of positioning the drill-arm in suitable angular positions with 90 relation to the post. The lower part of the column forms a bearing 25 about the post, split at 26, and clamped in adjusted positions by means of a clamp 27, similar to the clamp for the bearing of the drill-arm here- 95 inafter described.

The drill-arm is arranged to be adjusted up and down on the column, accomplished by means of a screw-shaft 30, having threaded connection with a threaded bearing 31 on the drill-arm, and journaled in a bearing 32 of the column and in a sleeve 33 fixed in a bearing 34 of the top 35 of the column, preferably fixed to the column.

Suitable means are provided for rotating 105 the screw-shaft in opposite directions, accomplished in the present exemplification by providing the screw-shaft with a gear 36 fast thereon. An upright shaft 37 is journaled in the column in a bearing 38 fast with 110

the post 27, a bearing 39 at the upper end of the post, and a bearing 40 in the top 35, the latter bearing having a bearing 41 in the post for guiding the top of the column.

5 Gears 42 and 43 are fast at the upper end of the shaft 37. The gear 43 meshes with a gear 44 journaled about a stud-shaft 45 fixed in a bearing 46 in the top of the column. A gear 47 is fast with the gear 44.

10 A quadrant-plate 51 is pivoted about the sleeve 33, about the axis of rotation of the screw-shaft. Pinions 54, 55, mesh with each other and are respectively journaled on studs 56, 57, fixed to the quadrant-plate 51, the pinion 55 being in mesh with the gear 36. The quadrant-plate is arranged to swing about its pivotal axis for causing the pinion 54 to mesh either with the gear 42 at the upper end of the upright shaft 37, or with the gear 15 47, the said gears 42 and 47 continuously rotating in opposite directions and thereby transmitting opposite directions of rotation to the screw-shaft 30, when the pinion 54 is placed in mesh with said respective gears.

20 25 The gear 44 is in train with a gear 58 fast at the upper end of a shaft 59, which has a bevel-pinion 60 splined thereto, arranged to move with the up and down movements of the drill-arm, for transmitting motion to the 30 usual drive-shaft extending lengthwise of the drill-arm for rotating and feeding the drill.

35 A rock-shaft 63 is journaled in a bearing 64 in the column and in a bearing 65 in the top 34. It is provided with an arm 66 fast thereon, articulated at 67 with a link 68 having articulation at 69 with the quadrant-plate 51. An operating arm 71 is fast on the rock-shaft 63, and has a latch 72 pivoted 40 thereon at 73, spring-pressed by a spring 74 into coaction with a notch 75 on the column, for maintaining the quadrant-plate in neutral position when the latch is in the notch, in which position the screw-shaft is inactive.

45 50 As hereinbefore stated, the drill-arm has a bearing 21 about the column, this bearing being a clamp-bearing. It is exemplified as provided with a plurality of incisions 76, 76, although it is obvious that the bearing, if desired, may be split throughout its length. Clamping means are provided for the bearing. I have exemplified a plurality of these clamping means. One or more may be employed within the spirit of my invention.

55 60 65 As exemplified, each of the clamping means consists of a clamp-screw 78, received through lugs 79, 80, at the respective sides of the incision in the clamp-bearing. The clamp-screw is exemplified as comprising a head 81 in which there are holes 82 for receiving a suitable spanner-wrench or key for turning the clamp-screw. The clamp-screw is arranged to be rotated in its bearing 86 in the lug 79 and to be secured in adjusted positions by means of the set-screw 87. The

clamp-screw passes through its bearing 88 in the lug 80.

A clamp-nut 90 is received about the threaded end 83 of the clamp-screw, and is exemplified as having an operating arm 91 70 thereon.

A washer 92 is interposed between the clamp-nut and the bearing 88, the washer being exemplified as a pluri-part washer comprising the parts 93, 94, having a ball-bearing 95 between them; the coacting faces between the washer and the bearing 88 being rounded, as shown at 96, so as to insure firm clamping contact between the clamp-nut 90 and the washer 92 and between the washer 92 and the bearing 88 over a substantial area, irrespective of the clamping relation of the clamp-bearing of the drill-arm, and to compensate for variations in parallelism between the axial lines of the 85 bearings 86 and 88 which take place during the clamping of the drill-arm bearing, and the variations there may be between said axial lines after wear has taken place between the clamp-bearing of the drill-arm 90 and the column, the bearing 88 having sufficient clearance, indicated at 97, with the clamp-screw 78 for permitting such slight variations as there may be in parallelism between the axial lines of said bearings 86 and 95 88, and the ball-bearing insuring ease of operation under great clamping strains.

If wear has taken place in the drill-arm bearing the clamp-screw 78 may be turned and clamped in new relation by the set-screw 87, so that the operating arm 91 will at all times extend in substantially the same direction when the drill-arm bearing is clamped for proper co-action of the locking means for the power-moving means for the 105 screw-shaft 30 hereinafter described.

In order to prevent the clamp-bearings from separating beyond the desired distance for permitting movement of the drill-arm, I provide a limiting bolt 98 which passes 110 through a bearing 99 in the lug 79 and is threaded in a threaded bearing 100 in the lug 80.

When a plurality of clamps is employed. I prefer to connect them, as by means of 115 a link 105, articulated respectively at 106, 107, with the operating arms 91 of the respective clamps, the operating arm 91 of the upper clamp being shown as provided with an operating handle 108.

120 Means are provided for connecting the operating means for the screw-shaft 30 and the clamping means for the drill-arm bearing, in order to insure release of the clamping means for the drill-arm bearing prior to actuation of the screw-shaft, for preventing excessive wear, damage and breakage of the parts.

125 It has frequently happened, for instance, in prior constructions, that the teeth of the 130

gears operating the screw-shaft have been stripped when the power was applied for rotating the screw-shaft while the clamp was in clamped relation.

- 5 In the present exemplification of my invention, I provide a lock 110 between the operating arm 91 and the rock-shaft 63, comprising, for instance, a pin 111 on the operating arm, coacting with a slot 112 in 10 a collar 113, rockable with the rock-shaft and exemplified as having spline-connection 114 therewith. The collar is arranged to move lengthwise of the rock-shaft with the adjustments of the drill-arm, accomplished, 15 for instance, by providing the collar with a groove 115 in which a bracket 116 secured to the drill-arm bearing is received. When the drill-arm bearing moves up or down, the collar is moved up and down with the 20 drill-arm bearing by the bracket 116, for maintaining the operative relation between the pin 111 and the collar.

While the pin 111 is in the slot 112, as exemplified in Figs. 7 and 8, rocking of the 25 rock-shaft 63 is prevented, making it necessary for the operator to first operate the operating arm 91 for unclamping the clamp-screw or clamp-screws 78, and thereby releasing the clamped relation of the drill- 30 arm bearing about the column, before rotation of the screw-shaft for moving the drill-arm up or down is possible, thereby preventing harmful results from carelessness or thoughtlessness on the part of the operator and insuring releasing of the drill-arm bearing prior to its axial movement.

On the other hand, return of the operating arm for the clamp to clamped relation prior to release of the power means of 40 the raising and lowering screw-shaft, will be prevented, because the slot 112 is out of registry with the pin 111 while the rock-shaft 63 is in any other than neutral position, the said slot being in registry position 45 with relation to the pin only when the latch 72 is in registry with its notch 75, the lugs 117 on the collar 113 being in obstructing relation with the pin when the latch is out of registry with its notch within the limits 50 of movement of the rock-shaft 63.

The groove 112 is preferably described on an arc having the pivotal axis of the arm 91 carrying the pin 111 as its center.

The locking means 110 as well as the 55 rock-shaft and screw-shaft move coincidentally with the drill-arm when the drill-arm is adjusted to different angular positions.

Having thus fully described my invention, what I claim as new and desire to secure by Letters Patent, is:

1. In a metal drilling machine, the combination with a column and a drill-arm, of means comprising a rock-shaft for adjust-

ing said drill-arm to height on said column, and means for clamping said drill-arm in adjusted positions to said column, said first-named means having lock-connection with said second-named means comprising a collar on said rock-shaft, means 70 for shifting said collar with said drill-arm lengthwise on said rock-shaft, and locking means coacting with said collar, said lock-connection releasable by manipulation of said second-named means.

2. In a metal drilling machine, the combination with a column and a drill-arm, of adjusting means adjusting said drill arm to height on said column, clamping means clamping said drill-arm in adjusted positions to said column, and locking means for locking said adjusting means in inactive relation operatively disposed between said adjusting means and said clamping means comprising a locking collar having opera- 85 tive connection with said adjusting means and adjustable to height with said drill-arm, and a coacting locking and unlocking part therefor controlled by said clamping means, and constructed and arranged for placing 90 said locking means in locked relation by clamping movement of said clamping means and in unlocked relation by unclamping movement of said clamping means.

3. In a metal drilling machine, the com- 95 bination with a column and a drill-arm, of adjusting means adjusting said drill-arm to height on said column comprising a train of gearing including a movable member mov- 100 able for active or inactive relation in said train of gearing, a rock-shaft for moving said movable member, clamping means for clamping said drill-arm to said column in adjusted positions, said clamping means comprising an arm, a collar rotatable with 105 said rock-shaft, and slot and pin connec- 110 tion between said clamping arm and said collar arranged for coactive relation during clamped relation of said clamping means and for release during unclamping relation of said clamping means.

4. In a metal drilling machine, the combination of a column, a drill-arm comprising a split-bearing about said column, means for raising and lowering said bearing ax- 115 ially on said column, and clamping means for clamping said bearing to said column in adjusted positions comprising a clamp- 120 screw and a nut therefor, constituting a pair of clamping members, bearings at the re- 125 spective sides of the split in said bearing for said clamp-screw, and a pluri-part washer between one of said clamping mem- bers and one of said clamp-screw bearings comprising a ball-bearing between the parts of said washer, said washer and said one of said clamp-screw bearings having rounded contact faces between them providing coact-

ing abutting faces of extended area irrespective of the parallelism of the axial lines of said clamp-screw bearings.

5. In a metal drilling machine, the combination of a column, a base, a drill-arm on said column swingable so as to project in different directions laterally over said base, adjusting means comprising a rock-shaft parallel with said column for adjusting said drill-arm to height on said column, clamping means clamping said drill-arm in adjusted positions to said column, and locking means locking said adjusting means and said clamping means together during maintenance of clamped relation of said clamping means, said locking means comprising a collar having operative connection with said rock-shaft to rotate therewith and move longitudinally thereof, and a coacting locking and unlocking part having operative connection with said clamping means, said locking means swinging and movable up and down with said drill arm.

6. In a metal drilling machine, the combination of a column, a drill-arm comprising

ing a clamp-bearing about said column, adjusting means adjusting said clamp-bearing to height on said column, a plurality of spaced-apart clamp-screws clamping said clamp-bearing in adjusted positions to said column, said clamp-screws provided with operating arms, a link articulated to said operating arms for connecting the same for combined movements, said adjusting means comprising a rock-shaft extending lengthwise of said column, a collar rotatively connected with said rock-shaft and movable lengthwise thereof with the movements to height of said clamp-bearing, one of said operating arms and said collar provided with slot and pin connection locking said rock-shaft against rotation during clamped relation of said clamp-screws.

In testimony whereof, I have hereunto signed my name in the presence of two subscribing witnesses.

HENRY DRESES.
